MACHINE FOR REDUCING MATERIAL

Alvah D. Hadsel, Oakland, Calif.

Application May 6, 1936, Serial No. 78,122
Renewed July 25, 1939

3 Claims. (Cl. 83—9)

The present invention relates to improvements in a method of and machine for reducing material and more particularly relates to the art of reducing ore or other substances.

It is proposed in the present invention to reduce the material by alternately striking a body of the material from opposite ends with sufficient speed and momentum to cause the body to remain in a state of suspension and to reciprocate for head-on collision with the reciprocating striking medium.

Reduction of the material is due not only to the impact at the end of each reciprocation but also to grinding action within the body on account of the rapid changes in the density and compactness of the material brought about by the opposing impacts.

While reciprocating motion of any character may be resorted to for the purposes of my invention, such as rectilinear motion, either in horizontal or in vertical, or angular direction, or reciprocating motion along an arc, as in a pendulum, I prefer, for the purposes of the present disclosure, to use the latter and the present description will be confined to the pendulum motion although I do not wish to limit myself thereby.

More particularly I propose to provide in the present invention a vehicle for containing a body of material which is supported as a pendulum and which is reciprocated at a speed sufficient to bring about relative motion between the vehicle and the charge contained therein so that the end walls of the vehicle during each return stroke strike the material moving in the opposite direction.

It is further proposed to shape the striking walls of the vehicle in such a manner that they exert a lifting effect on the body of material at each impact for aiding in holding the material in free suspension.

It is further proposed to provide means in connection with my machine for continuously removing from the vehicle material which has been reduced to a proper size, either by washing it through screens or by suction and to continuously feed new material into the vehicle.

Further objects and advantages of my invention will appear as the specification proceeds.

The preferred form of my invention is illustrated in the accompanying drawing in which

Figure 1 shows a longitudinal section through my machine, and

Figure 2 a transverse section taken along line 2—2 of Figure 1.

While I have shown only the preferred form of my invention I wish to have it understood that various changes or modifications may be made within the scope of the claims hereto attached without departing from the spirit of the invention.

In its preferred form my invention comprises a vehicle or container supported like a pendulum in the frame 2 and reciprocated by any suitable means as by the power shaft 3 and a connecting link 4.

The vehicle is preferably made substantially sector shaped, with two sector-shaped side walls 5 and a shell 6 connecting the edges of the side walls. This construction gives substantially a semi-cylindrical bottom to the vehicle and an upper portion comprising straight end walls converging toward the top which latter is suspended, with freedom of swinging motion, from the shaft 7.

Interiorly the lower cylindrical portion of the vehicle is reinforced by a series of rails 8 lining the shell in spaced relation to one another and fastened to the shell by means of bars 9 bearing on the base plates of the rails and bolts to the shell as at 10.

The side walls 5 of the vehicle are formed with openings 11 in the lower cylindrical portion of the vehicle and covering these openings I provide grid liners 12 and screens 13. The openings are used for washing out the fines, in which case the screens serve as a sizing medium. When suction is used for removal of the fines, as described in the next paragraph, these openings are closed and the draft passes from the hopper 35 opening through and below the material to the suction opening.

Above one of the openings I provide a feed hopper 14 and above the other opening a suction funnel 15 which is carried to the height of the shaft 7 and is connected, by means of a flexible medium, such as a rubber sleeve 16, to a stationary pipe 17 leading to a cyclone or other exhausting device, not shown in the drawing.

The supporting frame may be of any suitable construction and is here shown as being made of channel irons, with two longitudinal channels 18 and two transverse members 19 forming the base, two converging pairs of posts 20 rising therefrom and four horizontal members 21 connecting the posts at the top. Two of the latter members support the bearings for the shaft 7 from which the vehicle is suspended.

The drive shaft 3, which may be rotated from any suitable source of power, is supported in 55

bearings resting on horizontal members 22 supported at one end by short uprights 23 and bolted at their other ends to the uprights 20. The shaft has a crank 23' by means of which it operates 5 the connecting link 4 and is provided with fly wheels 24 on opposite sides of the crank. The connecting link 4 is connected to the vehicle through a shaft 25 carried by brackets 26 projecting from the vehicle.

10 My invention operates as follows:

A charge of material is placed in the vehicle, and, of course, drops on the bottom thereof. The vehicle is then set in motion to swing or reciprocate like a pendulum. As long as the swinging 15 motion is slow there will be little relative motion between the material and the vehicle, but as the speed is increased the material begins to roll back and forth in opposition to the vehicle movement, the momentum tending to overcome the force of 20 gravity until finally, when the operative speed is reached, the material is bodily lifted off the floor of the vehicle and is practically suspended in mid-air where it receives rapid blows from left and right from opposite walls of the vehicle in 25 alternate succession.

The amount of material fed into the vehicle is comparatively small relative to the capacity of the vehicle so that when the material is lifted in mid-air it occupies a relative small portion 30 in the central region of the vehicle, substantially as shown in the drawing so that there is ample room for the walls of the vehicle to move relative to the material.

As the vehicle starts to swing to the left from 35 an extreme right position it strikes the material from the right, imparting momentum in left-hand direction to the body of material. But in the meantime the left wall of the vehicle has proceeded far ahead of the material and when it reaches the extreme left-hand position there is 40 considerable space between it and the body of material. As the vehicle changes its direction and starts on its return trip the body of material is still moving toward the left so that there will be a head-on collision between the left wall of 45 the vehicle and the body of material. On account of this collision the body of material is made to change its direction, but now the right wall is far in advance of the material on the right side and strikes the body on its return trip, again in 50 head-on collision.

At each collision there is not only a crushing effect but also an internal friction and grinding effect since each blow is accompanied by a densifying of the body of material and transmission of movement from rock to rock followed by subsequent loosening.

While the reciprocating movement has a natural tendency to overcome the force of gravity the particular cylindrical shape of my vehicle causes the blows to be delivered partly from below in an upwardly inclined direction and partly from above in a downwardly inclined direction and thus aids in lifting the material away from the 60 bottom of the vehicle and also serves to concentrate the loose marginal material at each blow toward the center of the body of material.

For removing the fines from the vehicle I either employ water which may be fed into the 70 vehicle by any suitable means as by a pipe 27 and which washes the properly reduced particles through the screens 13 or the suction apparatus shown on the left side in Figure 2. It will be noted that the funnel 15 is carried upward to the 75 height of the shaft 7 where there is no side mo-

tion and where it may be safely connected to a stationary suction pipe by the flexible sleeve 16.

It is apparent that for successful operation of my invention a certain relation must be observed between the capacity of the vehicle, the load, the pendulum length of the vehicle between the supporting pivot and the center of gravity, the length of the stroke and the speed with which the vehicle is operated.

As has been pointed out the load must be comparatively light. If the vehicle were filled to capacity there would be no relative motion. In practice I fill the vehicle to less than one quarter of its capacity.

The length of the pendulum must be sufficient 15 to allow of a reasonable length of throw without departing too much from a horizontal plane. In the device illustrated in the drawing the length of the vehicle from pivot to center of gravity is approximately three feet and three inches.

The length of stroke or throw should be sufficient to allow the advance wall of the vehicle to get ahead of the body of material sufficiently to enable it, at the end of its movement in one direction, to return and to acquire a certain momentum 25 before striking the oncoming body of material. In the machine illustrated the total stroke from end to end is twelve inches.

The speed should be considerably in excess of natural pendulum speed. The machine shown 30 was designed to have a natural pendulum speed of 60 strokes. When completed it made 64 strokes per minute with the connecting rod detached. At this speed the mill required no theoretical power except to overcome friction and it could 35 be kept going at that speed with a slight pressure of the finger on the down stroke. With a charge in the mill the material began to move as soon as this speed was increased.

At 150 revolutions of the crank shaft the material seems to remain in suspension and is thrown from one side to the other with two impacts per revolution. At higher speed the charge does not travel far as the walls are traveling in 40 opposite directions so fast that crushing impacts are delivered in rapid succession without much movement of the charge.

From the capacity obtained in operation it is apparent that there must be considerable reduction between the particles themselves as well as at the points of impact with the vehicle walls.

I have not found it necessary thus far to use any crushing medium in the charge other than the rock itself but crushing media could be used if found advantageous.

A test run made by me recently with the machine illustrated showed a capacity of one and one half tons per hour feeding rock up to six inches in diameter and reducing same to forty mesh, with a power consumption of about six horsepower while the mill was running at 168 R. P. M.

I claim:

1. A machine for reducing material comprising a vehicle having a semi-cylindrical bottom portion, converging end walls rising therefrom and a pair of flat side walls, means for suspending the vehicle with freedom of pendulum motion, means for reciprocating the vehicle for reducing material contained therein, a chute carried by one 65 of the side walls, an outlet pipe carried by the other side wall, suction means and a flexible connection between the suction means and the outlet pipe arranged in alignment with the axis of the swinging movement.

2. A material reducing machine comprising a drum having a substantially semi-cylindrical bottom portion with walls rising therefrom, means for suspending the drum with freedom of pendulum motion, means for swinging the drum for throwing material in the drum in mid-air and for alternately striking the material from opposite ends with the wall of the bottom portion, and spaced rails on the bottom portion extending parallel with the axis of suspension to define material receiving pockets and to prevent slipping of material along said bottom portion.

3. A machine for reducing material comprising a vehicle adapted to contain material, means for suspending the vehicle with freedom of pendulum motion, means for reciprocating the vehicle for reducing the material, an outlet pipe carried by the vehicle, suction means, and a flexible connection between the outlet pipe and the suction means arranged in alignment with the axis of the swinging movement.
